UNITED STATES PATENT OFFICE

107,246

DESIGN FOR A FOOD CUTTING BOARD

Lewis M. Luteran and August P. Brunell, Clifton,
N. J.

Application July 28, 1937, Serial No. 70,705

Term of patent 7 years

To all whom it may concern:

Be it known that we, Lewis M. Luteran and August P. Brunell, citizens of the United States, residing in Clifton, county of Passaic, and State of New Jersey, have invented a new, original, and ornamental Design for a Food Cutting Board, of which the following is a specification, reference being had to the accompanying drawing, forming part thereof.

Fig. 1 is a plan view of a board embodying our new design; and

Fig. 2 is a lower edge view thereof.

We claim:

The ornamental design for a food cutting board, as shown.

LEWIS M. LUTERAN.
AUGUST P. BRUNELL.
